PROCESS OF TREATING
HYDROCARBON OILLe Roy G. Story, Beacon, N. Y., assignor to The
Texas Company, New York, N. Y., a corpora-
tion of Delaware

Application November 15, 1932, Serial No. 642,691

18 Claims. (Cl. 196—49)

This invention relates to the production of lower boiling hydrocarbon oils from higher boiling hydrocarbon oils.

It is an object of my invention to provide an improved process for the treatment of hydrocarbon oils for the production of high anti-knock value gasoline.

Another object is the provision of an improved process for reforming the heavy ends of natural gasoline obtained by stripping gasoline containing charging stock.

A further object is the provision of a process for coking heavy residual oil obtained as a by-product in the production of high anti-knock gasoline obtained by stripping gasoline containing charging stock.

Still another object is the provision of a process for lightly cracking fresh charging stock, which may or may not have a gasoline content, to produce cracked gasoline-like products and a residue, subsequently treating resulting cracked products to form high anti-knock gasoline, and using excess heat from the treating process to coke the charging stock residue.

In accordance with my invention a relatively clean hydrocarbon oil fraction is subjected to cracking in the vapor phase and is subsequently introduced into a soaking drum, after which the hot soaked products are combined with fresh charging stock and introduced into a low liquid level tower wherein separation of the lighter products, including any gasoline, from heavy residue-like oil results. The light products pass overhead as vapors and are introduced into a separator wherein a rough separation of the products into a light overhead vapor and heavier condensate is brought about, the light overhead vapor being subsequently transferred to a fractionator for further treatment and the condensate being removed from the separator and, if desired, combined with the stock subjected to the vapor phase cracking operation or otherwise treated.

In the fractionator the vapors undergo partial condensation, light products of the desired end point passing out from the top of the fractionator and thereafter being condensed and collected in a receiver. One or several naphtha side streams may be removed from the fractionator for further heat treatment and reformation in a separate stage which may comprise a cracking furnace wherein the products are raised to a relatively high temperature, e. g. 1050° F. and means for subsequently cooling and fractionating the cracked products to form a final desired distillate.

The residue resulting from the stripping of the

charging stock in the low liquid level tower is introduced into a coke drum, wherein heat from the hot reformed vapors is used to insure completion of the coking step. The heat exchange between the reformed vapors and residue may be carried out indirectly or directly. Vapors from the coke drum are transferred to an evaporator into which fresh charge may likewise be introduced and wherein light products are separated from a heavy residue. The light products are subsequently passed to a fractionator wherein reflux condensation takes place, the uncondensed vapors being either combined with those introduced into the fractionator first mentioned or passed through a condenser into a collecting drum, while the condensate is removed and used as the vapor phase charging stock for the vapor phase cracking operation first mentioned. The residue from the evaporator, being of a heavy character, is combined for coking with the residue from the low liquid level tower either before or after the passage of that residue in indirect heat exchange relation with the hot vapors from the reformation unit.

Direct heat exchange between the hot reformed vapors and the combined residues may be used where a larger amount of heat is needed for coking; in this case all three products would be introduced directly into the coke drum. Or a portion only of the hot vapors might be injected into the coke drum, the rest being passed either directly to a fractionator, or first in indirect heat exchange with the residue to aid in raising the latter to a coking temperature.

The above mentioned and further objects and advantages of my invention and the manner of obtaining them will be made clear in the following description taken in conjunction with the accompanying drawing.

In the drawing, reference numeral 1 indicates a vapor phase cracking furnace; 2 a soaking drum; 3 a low liquid level tower; 4 a separator; and 5 a fractionator. Clean charging stock such as gas oil having a boiling range of from 400—750° F. is introduced into the vapor phase heater 1 through line 6 by the action of pump 7 and is heated in the furnace to a high cracking temperature, for example 1000° F. under low or moderate pressure, for example 175—200 pounds per square inch, and is thereafter passed into soaking drum 2. After being digested in the soaking drum for a period of time, the vapors travel through conduit 8, wherein they are joined by fresh charging stock such as 31—32° A. P. I., M. C. gas oil, or a gasoline containing charging

stock such as 35-40° A. P. I., M. C. crude, introduced through pipe 9, the combined products subsequently entering low liquid level tower 3. This tower, which may be at a temperature of about 850° F. is preferably held at a reduced pressure by action of reducing valve 73, for example 50 pounds per square inch, in order to promote quick separation of the lighter products of the fresh charge and vapors from the heavier ends or residue, due, the lighter products passing overhead as vapors through pipe line 10 into separator 4, while the heavy residue is withdrawn from the bottom of the tower through conduit 11 and introduced into coke drum 12, to prevent any substantial accumulation of liquid in the tower. Additional pressure reduction may be accomplished by valve 74, but this usually will not be necessary. In the separator a portion of the light vaporous products is separated by condensation and removed through line 13, the uncondensed vapors passing out of the top of the separator through vapor line 14 to the fractionator 5. In the fractionator reflux condensation of the vapors occurs with the result that a product of desired end point is removed from the top of the fractionator through vapor line 15 and is subsequently passed through condenser 16 into receiver 17. This receiver is furnished with the usual gas drawoff line 18 and withdrawal pipe 20, both of which have suitable valves.

Line 21 is provided for withdrawing from the fractionator a side stream of gasoline fractions, e. g. heavy naphtha or comparable product, which is of such character as to require reformation in order to produce gasoline of a required high anti-knock value. This side stream is conducted through condenser or cooler 22 into manifold 23, from which it may be withdrawn by pump 24 and forced through line 25 and heating furnace 26 wherein it is raised to a reforming temperature, for example 975° F. under a moderate pressure, e. g. 400 pounds per sq. in. After leaving the furnace the reformed high anti-knock vaporous products pass through heat exchangers 27 and 28 into fractionator 29 wherein partial condensation of the vapors occurs and a final desired high anti-knock gasoline product is removed through vapor line 30 and condenser 31 for storage in receiver 32. This receiver has gas and liquid drawoff lines similarly to receiver 17, and the high anti-knock distillate which it collects may be blended with that segregated in receiver 17.

The residue withdrawn from the low liquid level tower may pass through heat exchanger 27 while the naphtha to be reformed may pass through heat exchanger 28 in any desired quantities, the flow of naphtha through the heat exchanger 28 being controlled by valves 33, 34 and 35. Reflux condensate from the bottom of fractionator 5 may be withdrawn through pipe 36 and either diverted from the system through pipe 37 having valve 38 or it may be passed through cooler 39 into the manifold 23 for passage to the reformation furnace 26. Valve 40 is for controlling the flow of condensate from the pipe 36 to manifold 23.

Vapors from the coke drum 12 pass overhead through pipe 41 into evaporator 42 where they may mingle with fresh charge introduced through line 43 having a control valve 44. In the evaporator separation of light vapors, including the vaporizable portions of the fresh charge takes place, the resulting vapors traveling through vapor line 45 into fractionator 46. The unvaporized portions of the products in the evaporator are withdrawn through drawoff line 47 and are

forced by pump 51 into the coke drum 12 in combination with the residue from the low liquid level tower 3. The residue from the evaporator 42 may either pass directly into the pipe line 11 to be combined with the residue from tower 3 prior to the passage thereof through the heat exchanger 27 or the residue may be introduced into the pipe line 11 near its point of connection with the coke drum 12, by proper manipulation of valve 48 in pipe line 49 and valve 50 in the line 47. The path of travel of the residue to the coke drum will be determined by the amount of heat necessary for the coking operation. The temperature of the coke drum may vary but should ordinarily be such that the vapors leaving the drum have a temperature of at least 840° F. If but a small amount of heat is necessary it may be found advisable to close the valve 50 and open the valve 48, thereby permitting the residue from the evaporator 42 to enter the coke drum at a moderate temperature and so exert a slight cooling effect upon the products entering the coke drum through the line 11. This optional arrangement permits of close control of the temperature in the coke drum. Uncondensed vapors from fractionator 46 travel to fractionator 5 through vapor line 62 having valve 63, for further treatment, or may be diverted to receiver 61 through pipe 64 and condenser 65, under control of valve 66.

Cooling coils 52, 53, 54 and 55 are provided in the tops of the chambers 4, 5, 29 and 46, respectively, in the usual manner. A receiver 56 is connected to the manifold 23 by pipe line 57, having a valve 58. This provides a means for removing from the manifold certain of its contained products if desired. A connection 59 is also furnished for conducting a portion of the distillate collected in receiver 17 into the manifold 23 if desired. It may be found advantageous in certain cases to reform this distillate, although in most cases it probably would be found best to reform only the heavy naphtha withdrawn through the pipe 21 as a side stream or that withdrawn through pipe line 36.

Added heat for coking may be obtained by introducing all or part of the hot reformed vapors directly into the coke drum 12; this may be done by proper manipulation of valves 59 and 60. In this case the desired final high anti-knock gasoline distillate is preferably collected in receiving drum 61, the valve 63 being closed to prevent the vapors from passing to fractionator 5, but re-treatment of the vapors in fractionator 5 may be carried out as before. Where the distillate is collected in drum 61 it may be blended with that collected in drum 16, if desired. The flow of residue through heat exchanger 27 is under control of valves 67 and 68 and by closing 68 and opening 67 the exchanger is rendered completely inoperative.

The condensate from fractionator 29, being relatively refractory, may well be introduced into drum 12 for coking. Valved line 69 is provided to accomplish this purpose. Cross-over line 70 serves to combine condensate drawn off from separator 4 with the residue from low liquid level tower 3, the routing of the condensate being controlled by valves 71 and 72, and the necessary pressure being supplied by pump 105. The character of this condensate can be controlled by the amount of fresh charge introduced into tower 3 and by the amount of cooling fluid passed through coil 52; when the amount of cooling supplied by the fresh charge and/or cooling coil 52 is relatively large, the condensate drawn off through 75

line 13 will be lighter in character and more suitable for treatment in vapor phase coil 1. With a lesser amount of cooling a heavier condensate results which is not so well adapted for treatment in a coil and is more profitably mixed with the residue for coking. Valved draw-off lines 109, 101, 102, 103 and 104 are provided for vessel's 3, 4, 29, 42 and 46 respectively, whereby products may be diverted from the system whenever desired. The vapor phase furnace 1 is adapted to heat the oil passing therethrough to a temperature of 900° to 1100° F., although a temperature of 950°-1040° F. is preferable, while the pressure on the oil in the vapor phase heater may range from 50-400 lbs. per square inch, but it is preferably in the neighborhood of 175-200 lbs. per square inch. The cracking per pass in the vapor phase coil and drum may range from 12 to 35% but is preferably from 20 to 25%. The temperature of the low liquid level drum may be from 800° to 900° F. but is preferably about 850° F. The reformation furnace may heat the oil to a temperature of from 900°-1050° F., and the pressure may range from 250-750 lbs. per square inch or higher; however, conditions of 975° F. and 175-200 lbs. per square inch will usually be found best. The fresh charging stock may vary considerably in character, for example it may range from 20° A. P. I., M. C. reduced crude to 35° M. C. gas oil or may comprise 35-40° A. P. I., M. C. crude but generally 31-32° A. P. I. gas oil will be found most suitable.

I have described a particular embodiment of my invention for purposes of illustration, but it should be understood that various modifications and adaptations thereof may be made within the spirit of the invention as set forth in the appended claims.

I claim:

1. The process of treating hydrocarbon oil which comprises raising a clean distillate to a vapor phase cracking temperature, combining the resulting cracked products while hot, in a stream of restricted cross-sectional area, with fresh relatively heavy charging stock in order quickly to raise the charging stock to a distillation temperature, subsequently reducing the pressure on the mixture and separating it in a separating zone into vapors and a liquid residue, fractionating resulting vapors to segregate a light gasoline distillate and a heavy naphtha condensate comprising gasoline constituents, raising said heavy naphtha condensate to a high cracking temperature in an independent heating zone to cause an increase in the anti-knock value thereof, removing residue from said separating zone at such a rate as to prevent the accumulation of any substantial body of liquid therein in order to prevent liquid phase digestion, passing hot vapors from the heated heavy naphtha in heat exchange with the removed residue, coking the heated residue in a coking zone, and removing vapors from said coking zone and passing them directly to a fractionating zone separate from said separating zone first mentioned to form a desired distillate.

2. A process in accordance with claim 1 wherein vapors from said coking zone are subjected to partial condensation to produce a light vaporous product and a clean condensate, said light vaporous product is combined with the light vapors introduced into the fractionating zone first mentioned and said clean condensate is utilized as said clean distillate stock first mentioned.

3. A process in accordance with claim 1 wherein vapors are removed from said coking zone and combined with fresh charging stock in a zone independent of said separating zone to produce light vapors and a heavy residue, said light vapors are subjected to fractionation, and said heavy residue is returned directly to the coking zone.

4. A process in accordance with claim 1 wherein vapors are removed from said coking zone and combined with fresh charging stock to produce light vapors and a heavy residue, said light vapors are subjected to fractionation, and said heavy residue is combined with said residue first mentioned prior to the passage thereof in said heat exchange relation with the hot reformed vapors.

5. A process in accordance with claim 1 wherein vapors from said coking zone are introduced into an evaporating zone independent of said separating zone in contact with additional fresh charging stock to produce vapors and a residue, said vapors are subjected to further partial condensation to produce light vapors and a clean condensate, and said clean condensate is utilized as said clean distillate stock first mentioned.

6. The process of treating hydrocarbon oil which comprises raising a clean distillate stock to vapor phase cracking temperature, combining the resulting cracked products while hot, in a stream of restricted cross-sectional area with fresh relatively heavy charging stock in order quickly to raise the charging stock to a distillation temperature, subsequently separating the mixture under reduced pressure in a separating zone into vapors and a liquid residue, fractionating resulting vapors in a fractionating zone to segregate a light gasoline distillate and a heavier gasoline fraction uncontaminated by residue, which it is desired to reform, raising said fraction to a high cracking temperature in an independent heating zone, thereby causing reformation thereof, removing liquid residue from said separating zone at such a rate as to prevent the accumulation of any substantial body of liquid therein in order to prevent liquid phase digestion, and reducing residue so removed to coke by aid of heat of the reformed products.

7. A process in accordance with claim 6 wherein said reformed products are combined while hot with said residue in a coking zone.

8. A process in accordance with claim 6 wherein said reformed products are combined with said residue in a coking zone wherein vapors are formed, and said vapors are subjected to fractionation to produce a condensate, said condensate being used as said clean distillate stock first mentioned.

9. The process of treating hydrocarbon oil which comprises passing a clean distillate stock through a heating zone wherein it is raised to a cracking temperature and subjected to conversion, passing resulting hot cracked products into a separating zone wherein vapors separate from liquid residue, introducing fresh charging stock into said separating zone in contact with the hot products therein to cause partial vaporization of said charging stock, withdrawing liquid residue from said separating zone at such a rate as to prevent the accumulation of any substantial body of liquid therein, removing vapors from said separating zone and subjecting them to fractional condensation to form a quantity of desired light distillate in the gasoline boiling range, an intermediate condensate comprising gasoline constituents which it is desired to increase in anti-knock value, and a heavy condensate, returning

- said heavy condensate to said heating zone, passing said intermediate condensate through a second heating zone wherein it is raised to a cracking temperature sufficient to cause conversion thereof into relatively high anti-knock gasoline constituents, separating the resulting cracked products into vapors and a liquid residue, fractionating said vapors in a separate fractionating zone to form an additional quantity of final desired light distillate and leave heavier products in liquid form, passing liquid residue withdrawn from said separating zone, in indirect heat exchange relation with hot products from said second heating zone prior to the fractionation thereof, to cause heating of said withdrawn residue to a higher temperature, and introducing the resulting highly heated residue into a separate coking zone subjecting it therein to coking by its contained heat.
10. A process in accordance with claim 9 wherein in said heavier products last mentioned are introduced into said coking zone in contact with the highly heated residue to undergo coking therewith.
11. A process in accordance with claim 9 wherein in a portion of the hot products from said second heating zone is passed directly into said coking zone to aid in the maintaining of the products therein at a suitable coking temperature.
12. A process in accordance with claim 9 wherein vapors are removed from said coking zone and subjected to fractional condensation to form an additional quantity of final light distillate, an intermediate condensate, and a heavy condensate, said heavy condensate is returned to said coking zone and said intermediate condensate is passed through said first mentioned heating zone for additional conversion.
13. The process of treating hydrocarbon oil which comprises passing a clean distillate stock through a heating zone wherein it is raised to a cracking temperature and subjected to conversion, introducing the resulting cracked products into a separating zone wherein vapors separate from liquid residue, removing vapors from said separating zone and subjecting them to fractional condensation to form a quantity of final desired light distillate, introducing crude oil containing gasoline fractions into said separating zone wherein partial vaporization thereof occurs by the heat of the cracked products, removing liquid residue from said separating zone at such a rapid rate as to prevent the accumulation therein of any considerable quantity of liquid in order to prevent liquid phase digestion, passing residue so withdrawn into a coking zone wherein it is subjected to coking, segregating a heavy gasoline fraction from the vapors removed from said separating zone, passing said heavy gasoline fraction through a separate heating zone wherein it is raised to a cracking temperature sufficient to increase the anti-knock value thereof, and subjecting

to reformation, separating the resulting reformed products into vapors and a liquid residue, fractionating the vapors to form an additional quantity of final desired light distillate, and utilizing heat derived from the hot reformed products to aid in carrying out the coking operation in said coking zone.

14. A process in accordance with claim 13 wherein said liquid residue withdrawn from said separating zone is passed in indirect heat exchange relation with the hot products removed from said second heating zone, prior to the introduction of the said residue into said coking zone.

15. A process in accordance with claim 13 wherein a portion of the hot cracked products from the said second heating zone is introduced directly into said coking zone to aid in maintaining the temperature thereof.

16. A process in accordance with claim 13 wherein vapors derived from the coking operation taking place in the coking zone are combined with vapors removed from said separating zone, for fractional condensation to form a desired light distillate.

17. A process in accordance with claim 13 wherein the fresh relatively heavy charging stock is combined with the hot cracked products formed in said first heating zone prior to the introduction thereof into said separating zone.

18. The process of treating hydrocarbon oil which comprises raising a clean distillate stock to a cracking temperature to cause conversion thereof, passing the resulting cracked products while hot in a stream of restricted cross-sectional area into a separating zone, introducing fresh relatively heavy charging oil into mixture with said cracked products in said stream in order quickly to raise the charging stock to a distillation temperature and separating the mixture in said separating zone into light vapors and a residue, fractionating said light vapors in a fractionating zone to form a light gasoline distillate and a side stream of heavy naphtha, raising said heavy naphtha, free from said residue, to a cracking temperature sufficient to cause an increase in the anti-knock value thereof, to cause reformation of said heavy naphtha, removing said residue from said separating zone and coking it by the aid of the heat of the reformed naphtha comprising heavy gasoline constituents, removing vapors from the coking operation and passing them directly to a fractionating zone separate from said separating zone first mentioned and subjecting them to fractionation to produce a clean condensate and light vapors of the desired end point, utilizing said condensate as said clean distillate stock first mentioned and condensing said light vapors last mentioned and combining this condensate with said light gasoline distillate to produce a final blended gasoline-like product of high anti-knock value.
